METALLIC CELLULAR BEVERAGE CASE

Otis C. Coles, Jr., El Paso, Tex.

Application April 9, 1948, Serial No. 19,966

2 Claims. (Cl. 220—21)

1

The present invention relates to beverage cases and is particularly well adapted for use in the storage and transportation of beverages put up in bottles. Such cases, sometimes called "flats" usually each have cells for receiving two dozen bottles.

In my copending application for patent on beverage cases filed concurrently herewith, Serial No. 19,965, I disclose forms of beverage cases made mainly of sheet material and heavy wire or rod reinforcing bands, which may be manufactured at a low cost, are durable, and light in weight. Such cases are capable of use with detachable cell forming means, which, by way of example, may be of the type disclosed and claimed in my copending application for patent on bottle spacers for beverage cases, filed concurrently herewith, Serial No. 19,967. In these copending applications, the forms specifically disclosed are particularly well adapted to receive the bottles in several rows, the bottles of any one row being in side by side relation to the bottles of any adjacent row, as is the practice with wooden cases or flats now commonly used.

Certain characteristics of the invention disclosed and claimed in my aforesaid application for patent on beverage cases may be utilized in the production of beverage cases made according to the present invention, but a principal object of this invention is to reduce the cost of manufacture of the cases by providing novel reinforcing bands and novel bottle spacing means associated therewith. Beverage cases made according to the present invention provide cells in which bottles of any given row are in staggered relation to the bottles of any next adjacent row, thereby reducing the width of the case over those in common use and of equal capacity.

Another object is to provide beverage cases which, while preferably made to each receive the standard number of twenty-four bottles, is novel in shape and appearance, being somewhat longer and narrower than the usual cases or flats, thus enabling a user to adopt this novel type of case to distinguish his goods from others or to distinguish a certain brand of his goods from another of his brands.

A further object is to provide beverage cases which, while having the bottle spacing means securely attached to the main body portions, in contradistinction to being removable, as in the copending applications above referred to, may be readily freed of trash or foreign matter so likely to accumulate in the cases while in transit and storage or while laying about empty or filled with empty bottles.

2

Other objects and advantages will appear in the following detailed description of a highly satisfactory embodiment of this invention, taken in connection with the accompanying drawings, forming a part of this specification and in which drawings—

Fig. 1 is a side elevational view of a beverage case constructed according to my invention.

Figs. 2 and 3 are, respectively, a top plan view and an end elevational view of the same.

Figs. 4 and 5 are, respectively, enlarged vertical sectional views on the lines 4—4 and 5—5 of Fig. 2.

Fig. 6 is a fragmentary view in plan of a reinforcing band suitable for use as a part of the beverage case.

Fig. 7 is an enlarged vertical sectional view on substantially the line 7—7 of Fig. 5.

In the drawings a body portion 11 is shown, equipped with an upper reinforcing band 12, and a lower reinforcing band 13. These bands support cell forming means 14.

The body portion 11 may be made from one piece of sheet material, and comprises a generally rectangular bottom 15, and side and end walls 16 and 17, respectively. The bottom 15 of generally rectangular, elongated formation, may be provided with longitudinally extending, up-struck, spaced, parallel ribs 20, each preferably of inverted V-shape cross section, to provide a crown 21, as shown in Fig. 5, and merging at substantially triangular shaped ends 22, into the main body of the bottom short of the ends thereof as shown in Fig. 2. These ribs serve to cushion the bottoms of the bottles when they are being placed in the case and during transportation, since the case body may be made of material of such gauge as to yield slightly or have a limited amount of resiliency at the ribs when the bottles are dropped thereupon or vibrated during transportation. The ribs also take up slack in the sheet material and give additional rigidity to the bottom as a whole.

The bottom 15 is preferably provided with notches 23 at its corners thru which trash and other foreign matter may be flushed or brushed, and the side and end walls preferably extend from the bottom between the margins of the notches, as shown in Fig. 2, whereby openings 24 are provided at the corners of the case body portion, as shown in Figs. 1, 3, 4 and 5. In this way damage by denting or breakage, due to rough handling, is alleviated since there are no rectangular bends of the body portion material at corners.

The upper reinforcing band 12, may be made

from heavy wire or rod material, bent to generally rectangular, elongated formation, in the example shown. This applies also to the lower reinforcing band 12. In effect, the corners are rounded as indicated at 25 so that in handling the cases or flats, no sharp corners or edges are presented at the upper portion of the case.

Each end wall 17 has a cut away portion 26 intermediate its ends 27 open to the top of the wall, providing a pair of upstanding tongues 28, the upper margins of which are curled over, in an inward direction, and about the upper reinforcing band 12, as indicated at 29, to provide a handhole 30 at each end wall beneath a run 31 of the reinforcing band, which latter serves as a handle for the case. Each wall 17 is also preferably provided with slits extending from and below the sides of the handhole 30 and the material between the slits is bent over to form a reinforcing flange 33.

The upper marginal portions of the side walls 16 are also curled over, in an inward direction, and about the upper reinforcing band 12, as indicated at 32. Thus these curled portions 29 and 32 form beading at spaced lengths about the upper margin of the case.

The lower reinforcing band 13 may also be made of heavy wire or rod material, and is disposed at the inside of the body portion 11 at the juncture of the bottom 15 with the walls 16 and 17 and is preferably of generally rectangular elongated shape so as to reinforce the lower portion of the body 11. The corner portions are rounded as indicated at 34 and traverse the space between the ends of the walls 16 and 17. The reinforcing band may be held in place by providing inverted U-shape cuts 35 in the walls 16 and 17 adjacent the band, and the material within the bounds of each of these cuts is curled inwardly and around the band as indicated at 36.

To this extent the body portion of the case may be similar in construction to that disclosed in my aforesaid copending application, Serial No. 19,965, except that it is preferred to make the former relatively long and narrow for the purpose hereinbefore set forth.

The cell forming means 14 comprises an upper series of sinuous wires 38 disposed with the sinuations in a horizontal plane, and a lower series of sinuous wires 39 disposed with the sinuations in a horizontal plane. These two series of wires are arranged so that for each wire of the upper series there is a wire of the lower series parallel thereto except at the end portions of the wires. The wires of each series are preferably arranged so that sinuations of each wire are inverse to the sinuations of each adjacent wire, thus providing a plurality of cells 40 for bottles, not shown in the drawing, which may rest on the ribs 20 as in the copending application Serial No. 19,965. It will be noted, however, that in connection with the present invention the cells are in staggered relation, thus making possible the production of cases which are narrower than the usual cases of flats having equal capacity.

In order that the wires 38 and 39 may be economically and rigidly secured in place, I prefer to provide the upper reinforcing band 12, at the ends of the case with a plurality of spaced off-sets or crimps 41 extending downwardly and inwardly toward the middle zone of the body portion, and the lower reinforcing band 13 at the ends of the bottom 15 with a plurality of spaced off-sets or crimps 42 extending upwardly and inwardly toward the middle zone of the body portion. Cer-

tain of the off-sets 41 may be provided in the zones of the tongues 28 of the end walls which are then provided with slots 43 at their upper portions, exposing the bight portions 44 of the off-sets for connection with the sinuous wires 38 as hereinafter described.

It is also preferred to dispose the intermediate portions of the wires 38 containing the sinuations, in a plane well below the top of the case, and to accomplish this, the ends of each wire may be bent upwardly as shown at 45 from its intermediate portion and secured to the band 12 by curls or eyes 46 embracing the off-sets 41 at their bight portions 44. In this way the cases may be stacked one upon another without likelihood of the wires 38 being damaged. The off-sets 41 also dispose the eyes well below the tops of the beads 29 so that they are not likely to be worn or damaged, since the gauge of the stock from which the wires 38 are made being less than the gauge of the stock from which the reinforcing band 12 is made.

It is also preferred to dispose the intermediate portions of the wires 39 containing the sinuations, in a plane well above the bottom 15 so as to effectively space the lower portions of any bottles placed in the cells and to permit of flushing of trash and foreign matter thru the openings 23 and 24. To accomplish this, the ends of each wire 39 may be bent downwardly, as shown at 48, from its intermediate portion and secured to the band 13 by curls or eyes 49 embracing the off-sets 42.

These off-sets 41 and 42 prevent the wires 38 and 39 from shifting laterally as do also the material of tongues 28 at each side of slots 43.

While the embodiment of the invention as herein disclosed, constitutes a preferred form, it is to be understood that other forms may be adapted, all coming within the scope of the claims which follow.

I claim:

1. In a beverage case, the combination of an elongated body portion comprising a bottom, side and end walls, and reinforcing bands at the upper ends of the body portion, said end walls each having a cut-away portion open to its upper edge, intermediate its sides, to provide a handhole with tongues at each side of the handhole, curled over and about its respective reinforcing band; said reinforcing bands each provided with spaced off-sets in the zones of the tongues of its respective side wall, said off-sets extending toward the middle zone of the body portion, and said tongues provided with slots exposing the bight portions of the off-sets; and cell forming means comprising a series of sinuous wires disposed with the sinuations in a horizontal plane, and having their end portions connected to said off-sets at the bight portions thereof.

2. In a beverage case, the combination of an elongated body portion comprising a bottom, side and end walls, and reinforcing bands at the upper ends of the body portion, said end walls each having a cut-away portion open to its upper edge, intermediate its sides, to provide a handhole with tongues at each side of the handhole, curled over and about its respective reinforcing band, said tongues of each end wall provided with slots at their upper portions exposing portions of the respective reinforcing band intermediate the curled portions; and cell forming means comprising a series of sinuous wires disposed with their sinuations in a horizontal plane, and having their end

5

portions connected to said reinforcing bar at said slots.
